REFRIGERATING APPARATUS

Lloyd M. Keighley, Dayton, Ohio, assignor, by
mesne assignments, to General Motors Corpora-
tion, a corporation of Delaware

Application December 27, 1932, Serial No. 648,940
Renewed April 10, 1934

14 Claims. (Cl. 62—4)

This invention relates to refrigerating apparatus and particularly to the control of such apparatus.

One of the objects of the present invention 5 is to provide a refrigerating system which automatically and normally maintains the desired refrigerating temperature for general refrigerating purposes and which will provide increased cooling automatically when it is desired, such as when 10 ice cubes are to be frozen or combustibles are to be congealed in the evaporator of the system, and which will automatically provide increased temperature of the evaporator at predetermined 15 timed periods to effect defrosting of the evaporator.

Another object of my invention is to provide an 20 improved refrigerating apparatus or system, including means which automatically modifies operations of the apparatus in response to certain demands or requirements placed upon the apparatus or in response to certain conditions of the apparatus, which will function automatically, to give preference to the effectiveness of one of the automatically operated devices included in the 25 system without interfering with continued operation of the system under the influence of that device and without interfering with subsequent operations of the other or both of the automatically 30 operated devices.

In carrying out the foregoing object, it is a further object of my invention to provide a refrigerating system or apparatus wherein there is included in the system a means for lowering the 35 temperature of the evaporator automatically, in response to the placing of a substance to be congealed or frozen in thermal association with the evaporator, and wherein there is also included in the system a means for effecting defrosting of the evaporator automatically at predetermined 40 timed intervals, with means for automatically and temporarily rendering the defrosting means ineffective when the means for causing a lower temperature of the evaporator, for quickly freezing a substance, is rendered effective.

Further objects and advantages of the present 45 invention will be apparent from the following description, reference being had to the accompanying drawings, wherein a preferred form of the present invention is clearly shown.

In the drawings:

Fig. 1 discloses a refrigerator cabinet shown in cross section and having my improved refrigerating system, shown diagrammatically, installed therein;

Fig. 2 is a sectional view taken on the line 2—2

of Fig. 3 of a control switch mechanism included in the refrigerating system;

Fig. 3 is a top view of the control switch shown in Fig. 2;

Fig. 4 is an enlarged sectional view of a magnetically operated valve included in my improved refrigerating system;

Fig. 5 is a fragmentary sectional view, taken on the line 5—5 of Fig. 1, of a portion of a clock or chronometric device also included in the system; and

Fig. 6 is a fragmentary elevational view of a portion of the clock or chronometric device shown in Figs. 1 and 5.

Referring to the drawings, for the purpose of illustrating my invention, there is shown in Fig. 1 thereof a compressor 20 for compressing refrigerant, such as sulphur dioxide contained in the refrigerating apparatus or system, and for forwarding the refrigerant to the condenser 21 20 where the compressed refrigerant is liquefied and collected in a receiver 22. From the receiver 22 the liquid refrigerant is forwarded through the supply conduit 23 to an evaporator 25 disposed in the refrigerator cabinet. The evaporator 25 25 may be of any suitable form such for example, as that shown in the patent to R. G. Osborn, No. 1,556,708, issued October 13, 1925. Liquid refrigerant entering the evaporator 25 through conduit 23 is maintained at a predetermined and substantially constant level therein by a float control valve substantially as shown in said patent to Osborn. Liquid refrigerant within the evaporator 25 absorbs heat and vaporizes, this vapor being returned to the compressor through the gaseous 35 refrigerant or return conduit 26. The compressor 20 is driven by an electric motor 27 through suitable belt and pulley connections 28. The electric motor 27 is supplied with electric 40 energy through an electric circuit which will be 45 hereinafter more fully described.

The evaporator 25 includes a header having a plurality of ducts depending therefrom to define a freezing zone. A sleeve or support 30 is supported within the freezing zone of the evaporator 45 25 and is adapted to receive and support a tray or receptacle 31. Evaporator 25 is located in an upper corner of an insulated compartment 32 of a refrigerator cabinet 33. The refrigerator cabinet may also include a lower machine compartment, closed by the door 34, and in which the refrigerant liquefying and circulating unit of the system is ordinarily housed. The insulated compartment 32 of cabinet 33 is divided into a food storage compartment and a cooling unit 50 55

compartment by any suitable partitioning means such as the baffle or partition 36. Partition 36 is provided with an opening 37 in the upper portion thereof and an opening 38 in the lower portion thereof to permit the ingress and egress of air circulated from the cooling unit compartment to the food storage compartment.

A control switch mechanism or device 40 is connected by a conduit 41 with a thermostat bulb 42. 10 Bulb 42 is located preferably in the upper portion of the food storage compartment 32 of cabinet 33 and is responsive to the temperature in compartment 32 and consequently of the evaporator 25. The control mechanism 40 and the 15 thermostat bulb 42 connected therewith, normally maintains the insulated compartment 32 and consequently evaporator 25 between predetermined temperature limits by opening and closing an electric circuit leading 20 to the motor 27 of the refrigerant liquefying and circulating unit, to provide alternate operating and idling periods of the compressor 20 according to the temperature in compartment 32, and consequently to the temperature of the evaporator 25. The foregoing description and disclosure of a refrigerating apparatus or system is conventional and is well-known to those skilled in the art of refrigeration. For this reason the description of the refrigerating system is made 30 brief and the system is only diagrammatically disclosed.

However, since my invention relates to the fully automatic control and function of a refrigerating system or apparatus which includes therein 35 means for automatically modifying the operation of the refrigerant circulating unit or for reducing the temperature of the evaporator of the system below its normal low temperature limit in response to the placing of a substance in the evaporator to be congealed or frozen and also includes means operated at predetermined time intervals 40 automatically for defrosting the evaporator of the system, to periodically remove frost or condensation of moisture collected on the evaporator 45 from the circulating air within the refrigerator cabinet, other auxiliary devices and a somewhat more elaborate electrical control circuit is essential to insure fully automatic and proper functioning of the system according to the objects of my invention. Therefore the refrigerating system 50 includes a device for modifying the operation of the refrigerant liquefying and circulating unit or for modifying the normal setting of the control mechanism 40 automatically to lower the 55 temperature of the evaporator below the normal low temperature limit thereof in response to the placing of a receptacle, such as the tray designated at 31 containing a substance to be frozen, in the freezing zone formed by the evaporator 25 60 or in the sleeve 30. In the present disclosure this device is incorporated in the control mechanism 40 and includes a conduit 44 connected with a thermostat bulb 45. Bulb 45 is secured in intimate thermal contact with the support or sleeve 65 30 upon or in which the tray 31 is adapted to be placed. The construction of this auxiliary device will be hereinafter more fully described and a description of its operation will accompany the description of the operation of the system. The 70 means for effecting automatic defrosting of the evaporator 25 of the refrigerating system at predetermined periods includes a device generally designated at 47 in Fig. 1 and associated with a clock or chronometric device generally designated at 48. The device 47 is connected in series

with the refrigerant conduit 21 forming the condenser and the device 48 is electrically connected with the device 47. A conduit 49 has one end thereof connected with the device 47 and has its other end leading to and communicating with the interior of the evaporator 25 preferably above the liquid refrigerant level therein. The construction of the auxiliary devices 47 and 48 for effecting defrosting of the evaporator will be hereinafter more fully described and a description of their operation will accompany the description of the operation of the system.

The thermal responsive means associated with the conduit 41 and bulb 42 of the system for actuating the control mechanism or device 40 comprises a hollow metallic bellows 54 (see Figs. 2 and 3) which is sealed at the top and which is connected at the bottom to the conduit 41. Conduit 41, bulb 42 and bellows 54 thereby provides a closed thermal system containing any suitable volatile fluid which vaporizes and liquefies or expands and contracts due to temperature changes for actuating the control 40. An operating lever 55 pivoted on ears 56 of the elevated platform 51 follows the movements of bellows 54 by being pivoted thereto by a pin 58. A double lever 59 straddles the lever 55 and is pivoted thereto by the pin 61. One end of the lever 59 is connected to one of the switch contacts 62 by a link 63. The cooperating switch contact 64 is mounted 30 on the base 65 of the control device. A snap action of the contact 62 with respect to its corresponding contact 64 is provided by a cam system which includes a steel nose 66, fastened to the other end of the lever 59, against which a 35 roller 67 is biased by a carrier 68 and a spring 69. As the pressure increases within the flexible metallic bellows 54, the latter expands and since the lever 55 is pivoted to this bellows by pin 58 and fulcrumed to the supporting frame of the device 40 as at 56, it is evident that the bellows will raise the operating lever 55.

The upward movement of the lever 55 is resisted by a yieldable adjustable system comprising a coil spring carried within an adjustable 45 casing 72 and bearing against a plunger 73 which acts against the extremity 74 of lever 55. When the pressure decreases and the bellows 54 collapses, the downward movement of lever 55 will be resisted by a coil spring 75 whose tension may 50 be regulated by nuts 76 carried on a vertical threaded rod 77 pivoted to lever 55. A balancing spring 78 adjusted by nuts 79 is used on the opposite side of the base 65 of the control device for resisting the tension of the spring 75. The 55 springs 75 and 78 and the resilient adjusting system comprising the plunger 73 and the adjusting cap 72 are provided for preferably so adjusting to produce what may be termed a normal predetermined adjustment, that is, for maintaining a pressure corresponding to a particular temperature in the thermal system 54, 41 and 42 which is ordinarily suitable under normal conditions for everyday operation of the evaporator in which the system is used. 65

The extremity 74 of the lever 55 bears against the plunger 73 only on the upward action of the lever 55. After lever 55 begins to descend the extremity 74 does not touch the plunger 73. Thus the plunger 73 effects the starting temperature 70 but not the stopping temperature. The cap 72 is therefore a starting adjustment. The temperature provided by the mechanism thus described is sufficient to maintain a substance contained in the evaporator in a frozen state after 75

it has been frozen by the evaporator or is sufficient to cool to the desired temperatures comestibles ordinarily stored in the insulated food compartment 32 of the cabinet 33. The control mechanism including the parts heretofore described is substantially identical to the control mechanism disclosed in the patent to Otto M. Summers, No. 1,802,486, issued April 28, 1931.

Since it is desirable to cause continuous operation or longer operating periods of the refrigerant liquefying and circulating unit instead of a plurality of short operating periods to rapidly reduce the temperature of the evaporator 25, and consequently the freezing zone formed in the evaporator, below their normal low temperature limit in event the evaporator or the freezing zone formed therein increases in temperature abnormally, I have provided means for modifying the operation of the refrigerant liquefying and circulating unit. The control means 40 is usually adjusted at the factory, or in the field by experienced service men, for such normal operation, by suitably tensioning the springs 76 and 78 as well as the resilient adjusting system 72 and 73. and in such condition the lever 55 will have its upward and downward movement resisted so that it will open and close the circuit of the driving motor 27 only at the maximum and minimum temperature points for which the tension 30 corresponds. By interposing a resistance to the descent of the lever 55, the operation of the switch contacts 62 and 64 will be delayed so that the system will operate continuously or will continue operating for a longer period of time, thus prolonging the cooling cycle of the system. Likewise if the resistance to the descent of the lever 55 is increased, it will require a greater effort on the part of the diaphragm or bellows 54 to pull the lever 55 down into contact breaking position. (The descent of the lever 55 causing the raising of contact 62 away from the contact 64 thus breaking the circuit.)

Therefore the auxiliary device, included in the system for automatically modifying the action of the control switch or for automatically interposing such a resistance to the control switch when it is desired, which communicates with the conduit 44 and bulb 45 includes a flexible bellows 81 fastened to the base 65 of the control device or mechanism 40 (see Figs. 2 and 3). The bellows 81, conduit 44 and bulb 45 provides a closed thermal system containing any suitable volatile fluid which vaporizes and liquefies and expands or contracts due to temperature changes. A pair of springs 82 have their lower ends attached to the base 65 of the control device 40 and have their upper ends connected to a cross strip 83 which rests on and may be fastened to the top of the bellows 81. Springs 82 normally maintain the bellows 81 in a contracted or collapsed position during normal operation of the system and therefore this bellows is out of contact with the control lever 55 and is consequently ineffective for adding resistance to the descent of lever 55.

Another electrical switch, comprising a closed glass tube 86 containing a small quantity of mercury, is associated with the control mechanism 40 and is adapted to be actuated only by movement of or expansion and contraction of the flexible bellows 81. The mercury tube 86 of this switch is pivotally mounted at its central portion by a yoke or shaft 87 to ears 88 formed on a support 89 secured to and extending upwardly from base 65 of the control device 40.

An actuating arm or finger 91, secured to and adapted to move with the bellows 81, engages and actuates the mercury tube 86 about its pivot 87 upon movement of the bellows 81. It is to be understood that the actuation of the mercury tube 86 is preferably a snap action for instantly moving the tube from its one tilted position to its other tilted position. Obviously the finger 91, in order to permit snap action of the tube 86, will be provided with an elongated opening to 10 permit free movement of tube 86 therein entirely from one tilted position to the other. Movement of the tube 86 from one tilted position to another causes the flow of mercury contained in the tube from one end thereof to the other. A pair of 15 electrical contacts 92 and 93 extend through and are sealed to the wall at one end of the tube 86 and a second pair of electrical contacts 94 and 95 extend through and are sealed to the wall of the tube 86 at the other end thereof. One or the 20 other of these pairs of electrical contacts, according to the position of the tube 86, are at all times bridged by the mercury within the tube. The contacts 92, 93, 94 and 95 are connected by wires 96, 97, 98 and 99 respectively to a terminal block 101 secured to the base 65 of the control 25 device 40 and are in turn connected to an electrical circuit to be hereinafter fully described.

The device 47 which is associated with the auxiliary device 48 for effecting defrosting of the 30 evaporator and which is actuated automatically at predetermined time intervals in accordance with the operation of the chronometric means or clock 48 (see Fig. 1) includes a valve 105 disposed within the housing 106 of the device 47 (see Fig. 35 4). Housing 106 includes a passage 107 extending therethrough and forming a part of the condenser conduit 21. The housing 106 is also provided with a passage 108 which is connected to the conduit 49 leading to the interior of the 40 evaporator 25. Passage 108 is adapted to communicate with the passage 107 and consequently with the high pressure on the interior of the condenser 21 but is normally closed off from passage 107 and condenser 21 by the valve 105. A plunger- 45 or enlarged portion 109 is formed on the top of valve 105 and thus plunger 109 is of sufficient weight to normally maintain the valve 105 in its closed position to seal the conduit 49 from the high pressure in the system, during operation of 50 the system to produce refrigeration, due to the small area of the valve 105 which is exposed to the pressure of refrigerant contained in the system. However in order to overcome the force exerted upon the valve 105 by the weighted plunger- 55 or portion 109, I provide a magnet or solenoid 110. Solenoid 110 may be of any conventional design and it is to be understood that when this solenoid is energized the plunger or portion 109 will be attracted by the solenoid and will be elevated to raise the valve 105 from its seat. Solenoid 110 is adapted to be connected to the clock or chronometric device 48 and to the electrical circuit to be hereinafter fully described, by attaching wires to the terminals 111 and 112 provided on the solenoid. 60

The means 48 for controlling predetermined timed periods of defrosting of the evaporator 25 of the refrigerating system includes a conventional clock or chronometric mechanism (not 70 shown) disposed within the casing 115 (see Fig. 5) and this mechanism may be of any suitable construction which constructions are well-known to those familiar with the art to which such mechanism belongs. The mechanism of the clock 75

or chronometric device 48 located within the casing 115 may, for example, be of the spring-wound type or it may be operated or driven by being connected in an electrical circuit. In either event it is to be understood that the operation of the mechanism disposed within the casing 115 of the means 48 is continuous irrespective of operations of the refrigerating system. A shaft 116 (see Fig. 5) of insulating material is preferably connected to the shaft of the hour hand of the clock or chronometric mechanism and is continuously rotated by the continuous rotation of the hour hand shaft. This shaft 116 extends through an opening 117 in a wall 118 of the means 48 and has a metallic finger 119 secured thereto by a screw or nut 121. A metallic collar 122 is loosely mounted on shaft 116 and is provided with an extension 123 which serves to provide a terminal for connecting a wire to the collar. Since the collar 122 is loosely mounted upon shaft 116 and is not rotatable by shaft 116 a spring 124 disposed between the collar 122 and an enlarged portion on shaft 116 is provided for holding the collar 122 in contact with the hub or finger 119 during rotation of shaft 116. Finger 119 carries a pair of brush contacts 126 and 127. Contact 126 engages a metallic member or substantially a ring 128 secured to and insulated from the wall 118 of the device 48 in any suitable manner such as by the insulating material 129. It will be observed by reference to Fig. 6 of the drawings that ring 128 has a portion thereof cut away or omitted from its circumference thus providing the ring with ends 131 and 132. It will also be observed that ring 128 is provided with a terminal 133 to which a wire may be secured. Disposed laterally from the space provided between the ends 131 and 132 and concentric with the ring 128 I provide a metallic conducting member 135 which is secured to the wall 118 by a terminal screw 136 and which is insulated from this wall by the insulating material 137. It is to be understood that member 135 is arranged in the space between the ends 131 and 132 of ring 128 and that contacts 126 and 127 are also arranged on finger 119 to insure that during the rotation of finger 119, by rotation of the hour hand shaft of the clock or chronometric mechanism within the casing 115, finger 119 will be in contact with either the conducting member 135, by engagement thereof by contact 127, or ring 128, by engagement thereof by contact 126, at all times (see Fig. 6). In other words when contact 126 on finger 119 moves beyond the end 132, during rotation of the finger the contact 127 on finger 119 will immediately engage or contact the member 135.

The electrical circuit interconnecting the control device 40 and the auxiliary devices 41 and 48 included in my system to insure fully automatic operation of the system as will be hereinafter more fully explained includes a wire 141 (see Fig. 1) leading from any suitable source of electrical energy to the contact 64 on the control switch or device 40. A wire 142 leads from wire 141 to the terminal block 101, wire 96 and contact 92 of the mercury tube switch on the control device 40. A wire 143 leads from the terminal block 101, and consequently from contact 93 and wire 97 of the mercury tube switch, to the terminal connection 111 on the solenoid 110. From contact 62 on the control switch 40 there is a wire 144 leading to the driving motor 27 of the refrigerating system. The wire 145 connects the motor 27 with the terminal block 101 and consequently by wire 98 with contact 95 of the mercury tube switch. The

motor 27 is also connected with the terminal 133 of ring 128 on the device 48 by a branch wire 146 leading from wire 145. A wire 147 leading from the terminal block 101 and consequently from wire 98 and contact 94 of the mercury tube switch 5 on device 40 connects with the source of the electrical energy. A branch wire 148 leading from wire 147 connects with the terminal 123, formed on the collar 122 surrounding the shaft 116, of the clock or chronometric device. It will be noted that the terminal 112 on the solenoid 110 is connected by a wire 149 to the terminal screw 136 of the member 135 on the device 48. The electrical connections between the control switch 40 of the refrigerating apparatus and other auxiliary devices included in my refrigerating system having been described I will now therefore proceed to describe the operation of the system under the influence of or the effectiveness of the various auxiliary devices. 20

In the operation of the system under the influence of thermostat bulb 42 and control switch 40 to maintain the evaporator 25 and consequently compartment 32 of the refrigerator cabinet 33 between normal predetermined refrigerating temperatures the motor 27 is caused to operate in response to the closing and opening of contacts 62 and 64 of the control switch 40. It is desired to herein point out that the thermostat 45 is ineffective for actuating mercury tube 30 switch during the maintenance of normal refrigerating temperatures in cabinet 33 and that the mercury tube switch will remain in the position shown in Fig. 2 of the drawings. The mercury tube switch while in this position completes the 35 electrical circuit from the source of energy through wire 141, wire 142, wire 96, contact 92, contact 93, wire 97 and wire 143 to the terminal 111 on solenoid 110 and from terminal 112 on solenoid 110 by wire 149 up to the member 135 40 and if the finger 119 of the device 48 is not in contact with the member 135 this circuit so far completed is interrupted at this point and energization of the solenoid 110 is prevented. If then the temperature of the compartment 32 of the cabinet 33 increases above the predetermined desired limit the thermal system connected with the thermostat bulb 42 and including the flexible bellows 54 will become effective to actuate the switch 40 to cause contact 62 thereof to engage 50 its corresponding contact 64. Upon engagement of the contacts 62 and 64 the electrical circuit from the source of supply to the motor 27 will be completed through wire 141, contact 94, contact 62, wire 144, wire 145, wire 146, terminal 133, 55 ring 128 on the clock or chronometric device 48, contact 126, finger 119, collar 122, terminal 123, wire 148 and to the side of the power circuit or wire 147 opposite wire 141. It is of course to be understood that the contact 126 on finger 119 of 60 the clock or chronometric device 48 must be in contact with the ring 128 in order to complete the circuit to the motor 27 to cause its operation. In other words the motor 27 will not be caused to operate by the making of contacts 62 and 64 on 65 the control switch 40 as just described unless the finger 119 of the clock or chronometric device 48 is in a position beyond that shown in the drawings wherein the finger 119 is over the conducting 70 member 135.

Operation of the refrigerant liquefying and circulating unit, by completion of the electric circuit as above described, will be interrupted by the effect of the thermal system including bulb 75

42, conduit 41 and bellows 84 on the control switch 40 after the temperature of the evaporator 25 and consequently the temperature of compartment 32, has been reduced to the desired or predetermined low limit. As above pointed out the mercury tube switch on the control device 40 is in the position shown in Fig. 2 of the drawings during normal operation of the system or while the thermal system comprising the bulb 45, 10 conduit 44 and bellows 81 is ineffective for modifying the action of the control switch 40. Consequently the electrical circuit to the solenoid 110 is made by contacts 92 and 93 through the mercury tube switch from the one side of the power line and through the solenoid 110 and is broken 15 at the clock or chronometric device 48 while this device is in its position to complete the circuit through the control device to the motor 27 of the refrigerating system. However, as soon as and 20 when the timing mechanism of the device 48 rotates the finger 119 in a clockwise direction beyond the end 132 of the ring 128 and out of engagement therewith the ring contact 127 on finger 119 will register with or contact the member 135. Engagement of contact 127 with the member 135 during the rotation of finger 119 by the clock mechanism thereby completes the electric circuit from the one side, wire 141, of the power line through wire 142, wire 96, contacts 25 92 and 93 on the mercury tube switch, wire 97 and wire 143 to the solenoid 110 and from this solenoid 110 through wire 149, terminal 136, member 135, contact 127, finger 119, collar 122, terminal 123, wire 148 to the opposite side, wire 147, of the power line. The solenoid 110 is thus energized and this energization of the solenoid directs and lifts the plunger or enlarged portion 189, to which the valve 105 is secured, upwardly. Lifting of the valve 105 from its seat in this manner permits hot refrigerant in the high pressure side of the refrigerating system, or in the conduit 21 of the condenser, to flow into passage 108, in the casing 106 of the device 47, through the conduit 49, and thence into the low pressure side of the refrigerating system or into the evaporator 25. This introduction of hot refrigerant from the condenser 21, into the cooling unit or evaporator 25, will of course, immediately raise the temperature of the evaporator and will cause frost or ice 50 accumulated on the walls thereof to melt therefrom.

Since defrosting of the evaporator is controlled by the clock or chronometric device 48 and this defrosting occurs preferably once a day or every 55 24 hours very little frost or ice will have accumulated on the walls of the evaporator 25 over this period of time. Therefore it is apparent that opening of valve 105 over a short period of time only, or the flow of a small amount of hot refrigerant from the condenser to the evaporator will cause the thin coat of frost or ice accumulated on the evaporator, over a period of time of 24 hours to be effectively removed therefrom. It is to be understood that the thermostats 42 and 60 45 are so located and arranged that there is a sufficient lapse of time before the heat of the refrigerant admitted to the evaporator, to effect defrosting thereof, can be conducted or transmitted to the thermostats 42 and 45. In this 65 manner the defrosting cycle of refrigerating apparatus or system is not prevented by the thermostats 42 and 45 and these thermostats will not affect the control switch 40 until after the temperature of the evaporator 25 or the temperature within compartment 32 has materially risen. In

other words the time lag between conduction or transmission of the heat of the refrigerant admitted to the evaporator and its effect upon the thermostats is sufficient to insure that this heat will melt frost from the walls of the evaporator. 5 However, if and when either thermostat 42 or 45 is affected by the heat of defrosting, to actuate or effect the control switch 40, defrosting of the evaporator 25 will have already occurred. It is therefore immaterial if thermostat 45 should 10 actuate the mercury tube switch on the control 40 into a position opposite that shown in Fig. 2 of the drawings to break the circuit through contacts 92 and 93 thereof and to the solenoid 110 or if thermostat 42 should actuate the contact 15 62 of the control 40 into engagement with the contact 64 to cause operation of the refrigerant liquefying and circulating unit. The reason such operation of the control device 40 is immaterial to my invention and likewise to the successful 20 operation of my refrigerating system is because of the fact that defrosting of the evaporator takes place quickly and previous to the actuation of the control 40 by the thermostats 42 and 45. The control switch 40 should on the other hand be in 25 a position to cause operation of the refrigerant liquefying and circulating unit immediately after defrosting of the evaporator has occurred, in order to again reduce the temperature of the evaporator 25 and the compartment 32 to the 30 desired low temperature limit, and the effect of the heat of defrosting on the thermostats 42 and 45 aids this requirement.

The essential and highly important feature of my improved refrigerating apparatus is to insure 35 that defrosting of the evaporator thereof cannot and will not occur at a time when a substance to be congealed or frozen is placed in the evaporator or while quick freezing of such substance is in progress. Accordingly when a warm substance 40 contained in a tray is placed in the freezing zone or sleeve 30 of the evaporator 25 the heat of this substance is immediately or quickly conducted to the thermostat 45, due to the thermal relation of thermostat 45 with sleeve 30, and this 45 heat causes the volatile fluid within the thermostat 45, conduit 44 and bellows 81 to expand. Expansion of the fluid in this thermal system causes expansion of bellows 81 and this bellows therefore moves into engagement with or into the path 50 of the lever 55 of the control device 40 thus actuating lever 55 to cause contact 62 to engage contact 64 of the control device and adds more resistance to the downward movement of the lever 55. When the contacts 62 and 64 are already 55 in closed position the bellows 81 will keep them in this position until after the substance in the ice tray has been frozen. Closing of contacts 62 and 64 when a substance is to be quickly frozen in the evaporator completes the electric circuit to 60 the motor 27 irrespective of the position of the finger 119 on the clock or chronometric device 48. By operating the motor 27 and consequently compressor 20 continuously over long periods of time until after the ice tray has been cooled, freezing 65 of substance contained in the tray is accelerated.

Movement of the bellows 81 to actuate the switch contact 62 into engagement with its corresponding contact 64 or to add resistance to the downward movement of lever 55 also actuates the 70 mercury tube switch into a position to break or open the circuit through contacts 92 and 93 of the mercury tube switch and to complete or make a circuit through contacts 94 and 95 thereof. Breaking of the circuit in this manner at 75

contacts 92 and 93 interrupts the power circuit to the solenoid 110 irrespective of the position of the finger 119 on the clock or chronometric device 48. The simultaneous making of the circuit at contacts 94 and 95 completes a circuit around the clock or chronometric device 48 so that the position of finger 119 thereon relative to the ring 128 or member 135 cannot interfere with the operation of the motor 27 of the refrigerating system during the modified operation of the system to quickly freeze the substance in the evaporator. Contacts 94 and 95 complete the electric circuit from wire 145 to the motor 27 and through wire 144, contacts 62 and 64, to wire 141 on the opposite side of the power line. The portion of the electrical circuit including wires 146 and 148, contacts 126 and 127, finger 119 and ring 128 controlled by the clock 48 is rendered ineffective for causing energization of the solenoid 110 and consequently defrosting of the evaporator cannot occur since the circuit from the solenoid 110 to the one side of the power line is broken at contacts 92 and 93 even if finger 119 should be rotated into communication with the member 135 during operation of the system under the control of the control device 40 while thermostat 45 is effecting the control 40. Movement or rotation of finger 119, on device 48, out of communication with ring 128 and into communication with the member 135 will not open or break the circuit to stop operation of motor 27, during operation of the system under the control of the control device 40 while thermostat 45 is effecting the same, due to the fact that the circuit through motor 27 is made by contacts 94 and 95 of the mercury tube switch and the wires leading from these contacts to the power line.

After the substance in the ice tray 31 has been congealed or frozen by the modified operation of the refrigerating system, fluid within the thermostat 45, conduit 44 and bellows 81 will contract and the springs 82 will pull bellows 81 downward out of the path of the arm 55 on the control device 40. The system and consequently the control 40 is then rendered operative to continue operation under the influence of thermostat 42 to maintain the compartment 32 of the refrigerator cabinet and consequently the evaporator of the refrigerating system between the desired predetermined normal refrigerating temperatures. Movement of bellows 81 downwardly likewise again actuates the mercury tube switch, on the control device 40, into the position shown in Fig. 2 of the drawings to break the circuit at contacts 94 and 95 and to make the circuit at contacts 92 and 93. The electrical circuit is thus again completed through the mercury tube switch to the solenoid 110 and this circuit is again under the control of the clock or chronometric device 48. Therefore as long as the system is in operation to maintain the evaporator 25 and the compartment 32 of the refrigerator cabinet between predetermined normal refrigerating temperatures, the electrical circuit of the system is operative to cause periodic defrosting of the evaporator under the control of or in response to the timing device or chronometric means 48.

From the foregoing it is apparent that I have provided an improved refrigerating apparatus which automatically maintains the evaporator thereof and consequently the compartment in which the evaporator is located between normal predetermined temperature limits and wherein operation of the system is modified automatically to operate continuously in response to the inser-

tion in the evaporator of a substance to be frozen. My improved refrigerating apparatus or system also includes means for causing defrosting of the evaporator at predetermined timed intervals which means is associated with the means for effecting quick freezing of substance placed in the evaporator of the refrigerating system in such a manner as to insure that defrosting of the evaporator will not and cannot occur when quick freezing of the substance by the evaporator is initiated or is in progress. It will also be apparent from the foregoing that the arrangement of the auxiliary devices and their association with one another insures that the refrigerating system will immediately be caused to operate in a manner different from the normal operation thereof when a substance is placed in the evaporator to be frozen irrespective of whether defrosting of the evaporator is taking place or whether the system is idle or operating under normal conditions.

While the form of embodiment of the invention as herein disclosed, constitutes a preferred form, it is to be understood that other forms might be adopted, all coming within the scope of the claims which follow.

What is claimed is as follows:

1. Refrigerating apparatus including a refrigerating liquefying and circulating unit and an evaporator adapted to receive a substance to be congealed or frozen operatively connected with said unit, means for controlling the operation of said unit to normally maintain said evaporator between predetermined temperature limits, means responding automatically to the temperature of a substance placed in intimate thermal association with the evaporator for modifying from normal the operation of said unit to lower the temperature of the evaporator below the normal predetermined low temperature limit thereof, means operable automatically in response to a certain duration of operation of said unit for causing the temperature of said evaporator to temporarily increase above the normal predetermined high temperature limit thereof, and means rendered effective automatically by the operation of said second named means for rendering said third named means ineffective.

2. Refrigerating apparatus including a refrigerant liquefying and circulating unit and an evaporator adapted to receive a substance to be congealed or frozen operatively connected with said unit, means for controlling the operation of said unit to normally maintain said evaporator between predetermined temperature limits, means responding automatically to the temperature of a substance placed in intimate thermal association with the evaporator for modifying from normal the operation of said unit to lower the temperature of the evaporator below the normal predetermined low temperature limit thereof, chronometrically operated means for causing the temperature of said evaporator to increase temporarily above the normal predetermined high temperature limit thereof, and means rendered effective automatically by the operation of said second named means for rendering said chronometrically operated means ineffective.

3. Refrigerating apparatus including an evaporator adapted to receive a substance to be congealed or frozen thereby and a refrigerant liquefying and circulating unit operatively connected with said evaporator, means for controlling the operation of said unit to cyclically circulate a refrigerating medium through said evaporator to

normally maintain the temperature thereof between predetermined temperature limits, means responding automatically to the temperature of a substance placed in intimate thermal association with the evaporator for modifying from normal the cyclical operations of said unit to lower the temperature of said evaporator below the normal predetermined low temperature limit thereof, means operable automatically in response to a certain duration of cyclical operations of said unit for causing the temperature of said evaporator to temporarily increase above the normal predetermined high temperature limit thereof, and means rendered effective automatically by the operation of said second named means for rendering said third named means ineffective.

4. Refrigerating apparatus including an evaporator adapted to receive a substance to be congealed or frozen thereby and a refrigerant liquefying and circulating unit operatively connected with said evaporator, means for controlling the operation of said unit to cyclically circulate a refrigerating medium through said evaporator to normally maintain the temperature thereof between predetermined temperature limits, means responding automatically to the temperature of a substance placed in intimate thermal association with the evaporator for modifying from normal the cyclical operations of said unit to lower the temperature of said evaporator below the normal predetermined low temperature limit thereof, chronometrically operated means for causing the temperature of said evaporator to increase temporarily above the normal predetermined high temperature limit thereof, and means rendered effective automatically by the operation of said second named means for rendering said chronometrically operated means ineffective.

5. Refrigerating apparatus including a refrigerant liquefying and circulating unit and an evaporator adapted to receive a substance to be congealed or frozen operatively connected with said unit, means for controlling the operation of said unit to normally maintain said evaporator between predetermined temperature limits, means responding automatically to the temperature of a substance placed in intimate thermal association with the evaporator for modifying from normal the operation of said unit to lower the temperature of the evaporator below the normal predetermined low temperature limit thereof, means for supplying heat to said evaporator to temporarily increase its temperature above the normal predetermined high temperature limit thereof, means associated with said third named means and operable automatically in response to a certain duration of operation of said unit for rendering said third named means effective, and means rendered effective automatically by the operation of said second named means for rendering said third named means ineffective.

6. Refrigerating apparatus including a refrigerant liquefying and circulating unit and an evaporator adapted to receive a substance to be congealed or frozen operatively connected with said unit, means for controlling the operation of said unit to normally maintain said evaporator between predetermined temperature limits, means responding automatically to the temperature of a substance placed in intimate thermal association with the evaporator for modifying from normal the operation of said unit to lower the temperature of the evaporator below the normal predetermined low temperature limit thereof,

means for supplying heat to said evaporator to temporarily increase its temperature above the normal predetermined high temperature limit thereof, chronometric means associated with said third named means for rendering said third named means effective, and means rendered effective automatically by the operation of said second named means for rendering said third named means ineffective.

7. Refrigerating apparatus including a refrigerant liquefying and circulating unit and an evaporator adapted to receive a substance to be congealed or frozen operatively connected with said unit, means for controlling the operation of said unit to normally maintain said evaporator between predetermined temperature limits, means responding automatically to the temperature of a substance placed in intimate thermal association with the evaporator for modifying from normal the operation of said unit to lower the temperature of the evaporator below the normal predetermined low temperature limit thereof, means for supplying heat to said evaporator to temporarily increase its temperature above the normal predetermined high temperature limit thereof, means associated with said third named means and operable automatically in response to a certain duration of cyclical operations of said unit for rendering said third named means effective, and means rendered effective automatically by the operation of said second named means for rendering said third named means ineffective.

8. Refrigerating apparatus including a refrigerant liquefying and circulating unit and an evaporator adapted to receive a substance to be congealed or frozen operatively connected with said unit, means for controlling the operation of said unit to normally maintain said evaporator between predetermined temperature limits, means responsive automatically to the temperature of a substance placed in intimate thermal association with the evaporator for modifying from normal the operation of said unit to lower the temperature of the evaporator below the normal predetermined low temperature limit thereof, means for supplying heat to said evaporator to temporarily increase its temperature above the normal predetermined high temperature limit thereof, chronometric means associated with said third named means for rendering said third named means effective, and means rendered effective automatically by the operation of said second named means for rendering said third named means ineffective.

9. Refrigerating apparatus including a refrigerant liquefying and circulating unit and an evaporator adapted to receive a substance to be congealed or frozen operatively connected with said unit, an electrical control switch operated automatically in response to the temperature of the evaporator for controlling the operation of said unit to normally maintain said evaporator between predetermined temperature limits, means responding automatically to the temperature of a substance placed in intimate thermal association with the evaporator for modifying from normal the action of said control switch and simultaneously modifying from normal the operation of said unit to lower the temperature of the evaporator below the normal predetermined low temperature limit thereof, means for supplying heat to said evaporator to temporarily increase its temperature above the normal predetermined high temperature limit thereof, means operable automatically in response to a certain duration

- of operation of said unit for controlling the operation of said second named means, and a second electrical switch operable automatically in response to the operation of said first named means for rendering said third named means ineffective for controlling the operation of said second named means and for simultaneously causing operation of said unit under the influence of the modified action of the control switch.
10. Refrigerating apparatus including a refrigerant liquefying and circulating unit and an evaporator adapted to receive a substance to be congealed or frozen operatively connected with said unit, an electrical control switch operated automatically in response to the temperature of the evaporator for controlling the operation of said unit to normally maintain said evaporator between predetermined temperature limits, means responding automatically to the temperature of a substance placed in intimate thermal association with the evaporator for modifying from normal the action of said control switch and simultaneously modifying from normal the operation of said unit to lower the temperature of the evaporator below the normal predetermined low temperature limit thereof, means for supplying heat to said evaporator to temporarily increase its temperature above the normal predetermined high temperature limit thereof, means operable automatically in response to a certain duration of operation of said unit for controlling the operation of said second named means, and a second electrical switch operable automatically in response to the operation of said first named means for rendering said second named means ineffective.
11. Refrigerating apparatus including a cooling element adapted to receive a substance to be congealed or frozen, a device connected with said cooling element and adapted to circulate a refrigerant medium therethrough, means for controlling the operation of said device to normally maintain said cooling element between predetermined temperature limits, means responding automatically to the temperature of a substance placed in intimate thermal association with the cooling element for modifying from normal the operation of said circulating device to lower the temperature of the cooling element below the normal predetermined low temperature limit thereof, means operable automatically in response to a certain duration of operation of said circulating device for causing the temperature of said cooling element to temporarily increase above the normal predetermined high temperature limit thereof, and means rendered effective automatically by the operation of said second named means for rendering said third named means ineffective.
12. A refrigerating system including an insulated cabinet having an evaporator located therein, control means for automatically controlling said system, means responsive to abnormal demands for refrigeration for automatically varying the operation of the system, a defrosting device for defrosting said evaporator, and means rendered effective automatically by the operation of said varying means for rendering said defrosting device ineffective.
13. A refrigerating system including an insulated cabinet having an evaporator located therein, control means for automatically controlling said system, means responsive to abnormal demands for refrigeration for automatically varying the operation of the system, a defrosting device for defrosting said evaporator, and means rendered effective automatically by the operation of said varying means for rendering said defrosting device ineffective.
14. A refrigerating system including an insulated cabinet having an evaporator located therein, control means for automatic control of said system, means responsive to abnormal demands for refrigeration for varying the operation of the system, a fully automatic defrosting device for automatically at intervals defrosting said evaporator, and means for rendering said defrosting device ineffective whenever said varying means responds to abnormal refrigeration demands.
